UNITED STATES PATENT OFFICE

2,391,636

GUN

Graham S. McArthur, Portland, Oreg.

Substituted for abandoned application Serial No. 467,312, November 30, 1942. This application March 20, 1944, Serial No. 527,236

1 Claim. (Cl. 89—1)

This invention relates to guns, and especially to rapid firing guns of large caliber. The primary object of the invention is to combine the forces of centrifugal force and combustion for the firing of projectiles.

This application is a substitute for my application Serial No. 467,312, filed November 30, 1942.

In the operation of this new and improved gun, the projectile is started through the barrel of the gun by velocity developed by centrifugal force, and it is further accelerated by gas or powder expansion timed to coordinate with the applied centrifugal force. It is believed that combining these two forces will produce greater striking power for the projectile, due to the fact that the projectile does not have to be started on its flight by the powder charge, but is only accelerated by this charge after it has acquired considerable momentum.

These and other objects will appear as my invention is more fully hereinafter described in the following specification and finally pointed out in the appended claim.

In the drawings:

Figure 1 is a side elevation of my new and improved gun.

Figure 2 is a slightly enlarged sectional end elevation taken on the line 2—2 of Figure 1.

Figure 3 is a sectional side elevation taken on line 3—3 of Figure 2, looking in the direction indicated.

Figure 4 is a perspective view of a rotor for creating centrifugal force for projecting the projectile.

Referring now more particularly to the drawings:

The gun comprises a barrel 1, formed integral with a cylindrical housing 2, which is mounted for rotation in a vertical plane with respect to a base 3, by means of standards 4, and horizontally mounted shafts 4A. The base 3, by means of ball-bearings 6, is manually rotatable by means of a worm 6A, carried by a shaft 7 and cooperating with a worm gear 8 secured to, or formed around, the base 3, for convenience of operation, the shaft is provided with a hand wheel 9.

A worm gear 10, is secured to, or formed around, the periphery of the housing 2, and is operatively engaged with a worm 11, carried by a shaft 12, terminating in a hand wheel 13 for raising or lowering the gun barrel in a vertical plane.

A rotor 14, is mounted for high speed rotation without the housing 2, by means of hollow shafts 15 and 16, journaled within bearings 17 and 18,

respectively. The rotor is driven by a motor or other power source 19, carried by an extension 20, of the base 3, and operatively coupled with a reduced extension 16A, of the shaft 16, by means of sprocket wheels 21 and 22, embraced by a sprocket chain 23. Slidably and yieldingly mounted within the hollow shaft 16, is a shaft 24, whose one end is in contact with a bell crank 25, and whose opposite end engages with a rocker arm 26. The opposite end of the rocker arm is connected with a gate 27, slidably mounted in a thickened wall portion 28, of the rotor 14. This wall portion is radially bored as at 29. The bore terminates in the hollow shaft 15, whose outer end may be disposed adjacent any approved type of mechanism (not shown) for feeding projectiles 30, into the bore. The projectiles are released one at a time, by the gate 27, and thrown by centrifugal force into the bore of the gun barrel 1.

The gate 27, is operated to open and close at properly timed intervals by means of an arm 31, connected at one of its ends to one leg of the bell crank 25, and at its opposite end to a plunger 32, which carries a roller 33, disposed in the path of travel of a cam 34. The cam is formed on a sprocket wheel 35, secured to the shaft 36, of a pressure generator, generally indicated at 37. The generator, through sprocket chain 37A, is driven by the motor 19, by means of a sprocket wheel 38, secured to the shaft 16, of the rotor. The pressure generator comprises a cylinder 39, mounted to a crank-case 40, in any approved manner. A piston 41, is mounted within the cylinder and connected by connecting rod 42, with a crank-shaft 43, the crank 44, of which is formed with a cam 45. The crank-shaft is formed with a cam 46, cooperating with a rocker arm 47, to open and close an air intake valve 48, in the head of the pressure generator through the medium of push-rod 49, and rocker arm 50.

Arranged alongside the cylinder 39, is another cylinder 51, having a piston 52, slidably mounted therein which is connected by a rod 53, with a rocker arm 54, whose one end is in rolling contact with the cam 45, on the crank 44. One end of the piston 52, is reduced in diameter as at 55, and terminates in a valve 56, cooperating with a valve seat 57, formed in one wall of a combustion chamber 58. The combustion chamber communicated with the gun barrel through a duct 59. A combustible fluid is fed, intermittently, into the combustion chamber through a feed pipe 60, and fuel nozzle 61, in timed relation to the rotation of the crankshaft in the conventional manner. The piston 41, upon moving to the left, as viewed in

Figure 3, draws in a combustible charge and on the return stroke compresses the charge while the valve 48, remains closed. At the completion of the compression stroke, the spark-plug 62, fires and ignites the charge, whereupon the piston 41, is driven on a downward stroke, or to the left as viewed in Figure 3, but, during said movement of the piston to the left, the valve 56, opens and allows the force of the explosion to pass through duct 59, into the gun barrel directly behind the projectile 30, which, as aforesaid, has now been started on its way by the centrifugal force of the rotor.

The follow-up of the explosion is timed to add its force to the projectile in flight immediately after it is started on its way, in contrast to a projectile which is moved from a standing start and propelled thereafter by the one charge of explosive, and wherein a percentage of the explosive is dissipated in getting the projectile started before the remainder of the explosive is useable to further project the same. In contrast to this, my invention utilizes the entire force of the explosion to accelerate the projectile and none of it is lost in overcoming the inertia of the projectile.

since the projectile is started on its way by centrifugal force as aforesaid.

While I have shown a particular form of embodiment of my invention I am aware that many minor changes therein will readily suggest themselves to others skilled in the art without departing from the spirit and scope of the invention. Having thus described my invention, what I claim as new and desire to protect by Letters Patent is:

A gun comprising a cylindrical housing in open communication with a gun barrel, a rotor mounted within the housing, means for continuously rotating the rotor, the bore of said gun barrel being tangential to the periphery of the rotor, said rotor having an axial inlet and a peripheral outlet for the passage of projectiles therethrough, means at said outlet for intermittently releasing the projectiles to be thrown forwardly through the gun barrel by the centrifugal force of the rotor, a pressure generator in timed intermittent communication with the gun barrel and adapted to direct pressure behind the projectile immediately upon its entrance into the gun barrel.

GRAHAM S. McARTHUR.
